I. M. PEASE

TRUSS

Filed Feb. 24, 1925

INVENTOR:

Isaac M. Pease,

BY

Arthur D. Ewald,

ATTORNEY.

UNITED STATES PATENT OFFICE.

ISAAC M. PEASE, OF CINCINNATI, OHIO, ASSIGNOR TO THE OHIO TRUSS COMPANY, A CORPORATION OF OHIO.

TRUSS.

Application filed February 24, 1925. Serial No. 11,203.

My invention relates to trusses and particularly to trusses of the so-called hood type.

Trusses of the type mentioned, as heretofore constructed, comprised two springs adapted to fit around the sides of the wearer, the front ends of such springs being attached to the hood support, which is a curved bar arranged to support remedial pads in contact with the person of the wearer; the rear ends of the springs are open and are also adapted to carry pads which bear against the back of the wearer so as to retain the front hood supported pads in position. The hood support in trusses of this type has been of rigid construction and therefore it has been found difficult in many instances to obtain the proper pressure of the front pads.

The principal object of the present invention is to provide a truss in which this difficulty is entirely overcome, and the front pads properly supported in contact with the condition to be remedied, without adding any to the pressure of the rear.

Further objects of the invention will appear from the following detailed description thereof.

In the drawings:

Figure 1 is a plan view of a truss constructed in accordance with this invention, the dotted lines showing the position of the truss spring when not in place on the wearer.

Figure 2 is a plan view of the continuous truss spring.

The numeral 1 indicates a continuous spring curved at the sides 2 and 3 in accordance with the usual plan, so as to encircle the person of the wearer in proper manner to support the truss pads. The rear, free ends 4-4 of the spring are adapted to receive the usual back pads 5-5 which may, and preferably are, adjustable on the spring so as to accommodate the person of the wearer. The rear ends may be secured further when the truss is in position by the usual strap 6. The springs are provided with leather or other suitable sheathing 7, in accordance with the usual custom. The front portion 8 of the spring is of the same

material construction as the sides 2 and 3, that is, it is of spring construction and has the same resilience, being, in fact, unitary with the other portions of the truss spring. Said spring is adapted to carry the usual 55 remedial pad or pads 9, and a short leather or other sheathing 10 may be interposed between said pads. The pads 9 are adjustable on the spring in accordance with the usual practice.

When a truss of continuous spring construction, as above described, is not in use, that is, when it is not upon the person of the patient, the spring assumes a general contour, as shown in broken lines in Figure 1, and in full lines in Figure 2, the front portion of the spring extending relatively farther forward of the transverse axes of the spring than when the sides 2 and 3 are bent, so as to bring the rear pads 5 in position on 70 the wearer, as shown in full lines in Figure 1. This bending carries the front portion of the spring inwardly toward the person of the wearer, carrying with it, of course, the pads 9, and therefore increasing the pressure and serving to ameliorate the condition to be treated, without increasing the pressure of the rear pads 5. Where, however, the front or hood support for the pads 9 is of rigid construction, the bending of the 75 sides 2 and 3 does not affect the position of the pads relative to the transverse axes of the truss.

Having thus fully described my invention, what I claim as new and desire to secure by 80 Letters Patent is:

1. In a truss, a continuous one-piece spring of uniform resilience adapted to encircle the person of the wearer, said spring being open in the back, pads mounted on 85 the rear ends of said spring, and a pad mounted on the front portion of said spring.

2. In a truss, a continuous one-piece spring of uniform resilience adapted to encircle the person of the wearer, said spring being open in the back, pads mounted on the rear ends of said spring, a pad mounted on the front portion of said spring, and a sheathing for said spring.

ISAAC M. PEASE.
